SELF-CLOSING TUBE AND CAP

Horace William Goss and Reginald Griffin Goss,
Toronto, Ontario, Canada

Application March 15, 1937, Serial No. 130,846

3 Claims. (Cl. 221—60)

The invention relates to collapsible dispensing tubes and more particularly to improvements in self-closing dispensing means therefor.

The principal object of this invention is to provide a simple form of dispensing device which may be incorporated in or applied to a collapsible type of tube container at low cost and which will be very convenient to operate.

The principal feature of the invention resides in the novel construction and arrangement of the parts whereby a slide valve is normally held to its closed position by means of a resilient or elastic element encircling the neck of the container or cap.

15 In the drawing Figure 1 is a perspective view of the upper end of the collapsible container tube showing a preferred form of the present invention applied thereto.

Figure 2 is a mid-sectional elevation through the construction shown in Figure 1.

20 Figure 3 is a plan view showing the valve in open position.

Figure 4 is a side elevational view of the upper portion of a dispensing container showing a modified form of resilient closing means for the valve.

25 Figure 5 is a view similar to Figure 4 illustrating a further modified form of elastic closing means.

Figure 6 is a perspective detail view illustrating 30 a modified form of valve operating means.

Figure 7 is a perspective view of the upper portion of the container illustrating the present invention applied to the removable cap thereon with the valve closed.

35 Figure 8 is a view similar to Figure 7 showing the valve in its open position.

Figure 9 is a mid-sectional elevational view through the construction shown in Figure 7.

40 Figures 10 and 11 are mid-sectional elevational views showing the slidable valve associated with a sealed puncturable outlet.

Many forms of self-closing dispensing valves have been previously proposed in connection with collapsible containers and the like, but these have 45 invariably been of a more or less complicated nature which were unduly costly in production or involving various difficulties in assembly, and the present invention has been devised to provide a self-closing valve which will be of extremely simple form which will involve no difficulty in assembly and which will not add appreciably to the cost to the consumer and which will be very simple to operate.

45 In the construction shown in Figures 1 to 3 the collapsible tube container 1 is shown terminating

in a neck portion 2 of reduced size and provided with a transverse under-cut guideway or slot 3 on the outer end extremity and a dispensing opening 4 leads into the guideway.

A slide valve member 5 is shaped to slidably fit 5 or interlock with the undercut sides of the guideway 3, and has a downward hooked extension 6 at one end and an elastic band 6' is applied under tension about the neck 2 and engaged in the hooked extension 6 so that the valve is held in 10 its closed position overlapping the opening 4 with the opening 8 of the valve out of register with the opening 4 and with the end portion 5' projecting beyond the side wall of the neck, to be conveniently pressed inward as by the thumb or 15 finger when it is desired to open the valve in which position it is shown in Figure 3.

In Figure 4 the elastic element 7' is shown in the form of a coiled spring encircling the neck, while in Figure 5 an elastic band 7' of wider and 20 flatter form is shown.

In the form shown in Figure 6 the elastic element comprises a length of spring wire 9 which is bent to encircle and clamp about the neck 2 of the container and is provided with a spring extension 9' at one end which is co-operatively associated with the valve 5 to hold the same in its closed position so that the opening of the valve 25 is effected against the spring tension.

In Figures 7 to 9 the valve 5 is shown slidably 30 mounted in an undercut slot 3' which is formed across the removable cap 10, which cap together with the valve may be provided as an accessory or as standard equipment having a threaded neck 2' threaded to removably fit on the threaded 35 neck 2'' of the container. In this form of the invention the elastic band or other resilient element 7' encircles the neck portion 2' of the removable cap.

In Figures 10 and 11 the dispensing opening 4' 40 of the collapsible tube is shown of the type which is sealed by a thin puncturable diaphragm 4'' which may be punctured by inserting a suitable instrument through the valve opening 8' as shown in Figure 11, so that thereafter the valve 5 will 45 serve to open and close the punctured opening.

The use of an ordinary elastic rubber band in the environment set forth serves a new and useful purpose and although of infinitesimally small cost it ensures the proper closing of the dispensing valve, and it will be apparent that the assembly may be effected with no difficulty whatever, and this ease of assembly is also present in all forms of the invention illustrated by reason of the fact that the resilient element only requires 50 55

to be slipped into position over the top of the container or cap to establish its co-operative relation with the valve.

What we claim as our invention is:

- 5 1. In a dispensing container having a dispensing opening and a valve slidably mounted to open and close said opening and having an angularly arranged extension formed with a hooked extremity, an elastic band encircling said container and extending about said valve extension and holding said valve closed, said hooked extremity co-operating with the elastic band to hold same in position, the arrangement of the valve and elastic band being such that the band 15 normally retains the valve with its other extremity overhanging the said band to further retain same in position.
2. The combination with a dispensing tube having a threaded neck, of a cap threaded to receive 20 said neck, said cap having a bottomed slot ex-

tending diametrically thereof on the outward side and having a dispensing opening in the bottom of less width than the slot, a slide valve reciprocably mounted in said guideway and having sealing engagement with the bottom of said guideway 5 completely about the dispensing opening free of contact with the neck or body of said tube, and resilient means engaging only said cap and valve for urging said valve to its closed position.

3. Means as claimed in claim 2 in which said 10 resilient means comprises an endless elastic band encircling the threaded portion of said cap under tension and engaging a portion of said valve, said cap, valve and elastic band comprising a complete, removable unit with the elastic band as- 15 sembed therewith under tension independent of the dispensing tube.
